[57] CLAIM

The ornamental design for a graduated feeding bottle, as shown and described.

DESCRIPTION

FIG. 1 is a front view of one embodiment of a graduated feeding bottle showing my new design; the rear view being a mirror image thereof;

FIG. 2 is a left side view of the feeding bottle illustrated in FIG. 1;

FIG. 3 is right side view of the feeding bottle illustrated in FIG. 1;

FIG. 4 is a front view of another embodiment of a graduated feeding bottle showing my new design, the rear view being the mirror image thereof;

FIG. 5 is a left side view of the feeding bottle illustrated in FIG. 4; and,

FIG. 6 is a right side view of the feeding bottle illustrated in FIG. 4.
